UNITED STATES PATENT OFFICE

WILLIAM F. SNEED, JR., OF LAKELAND, FLORIDA

CRATE

Application filed April 23, 1931, Serial No. 532,312. Renewed November 1, 1932.

The present invention relates to improvements in crates, and has for an object to provide an improved crate for containing bottles such as bottled coca cola, or other goods or merchandise, in which the parts are simple, inexpensive, strong and rigid.

Another object of the invention resides in providing an improved bottle or other crate wherein the repairs will be less than those ordinarily encountered in conventional crates as manufactured and used in the bottle and other industries today, and the parts of which can be readily replaced when worn or broken without entailing the relatively great expense of discarding the entire crate in favor of a new one.

A further object of the invention resides in providing improved partitions and reinforcements therefor, which are adaptable to any form of crate and which when placed in a wooden box or crate will reinforce and strengthen the same and convert such box or crate into an unusually strong, rigid and attractive carrier for bottles and the like goods.

With the foregoing and other objects in view, the invention will be more fully described hereinafter, and will be more particularly pointed out in the claim appended hereto.

In the drawing, wherein like symbols refer to like or corresponding parts throughout the several views,

Figure 1 is a plan view of my improved crate with parts broken away.

Figure 2 is a vertical section along the line 2—2 of Figure 1, and

Figure 3 is a transverse section taken along the line 3—3 of Figure 1.

Referring more particularly to the drawing, 5 represents the base or bottom of an ordinary wooden box or crate, 6 the side walls also of wood, and 7 the end walls likewise of wood. The side and end walls 6 and 7 are erected on the base 5 in any usual or conventional manner, the top of the crate or box being left open in the usual manner.

In accordance with the invention, I apply to the upper portion of the crate a plate 8 of sheet metal or other appropriate material, which plate will be substantially rectangular

and of an overall length and width extending beyond the sides and ends 6 and 7 of the crate structure, whereby the margin portions of the plate may rest upon the upper edges of said side and end walls 6 and 7, there being a surplus of material of the plate 8 left over beyond such side and end walls, which surplus material may be turned down along the exterior faces of the side and end walls 6 and 7. The flanges 9 thus produced will serve to center the plate 8 upon the crate and the plate will be reinforced at its marginal portions by this flange. The crate itself will also be reinforced by the flange 9, which may be secured, as by the nails 10 or other fastenings, to the side and end walls 6 and 7. In the plate 8 are produced openings 11 preferably surrounded by down-turned flanges 12. These openings may be stamped from the sheet metal of the plate 8, sufficient material being left from the stamping operation to constitute the flanges 12, which flanges may be produced in the stamping operation.

The flanges are preferably curved so as to form smooth surfaces and to readily receive the bottles, one of which is indicated in dotted lines at 13 in Figure 2.

In the lower portion of the crate I mount a similar sheet metal or other plate 14 having openings 15 therein for the bottles or other goods, which openings are surrounded by the reinforcing flanges 16. The side margin portions of the lower plate 14 are turned downwardly to constitute legs 17 resting upon the bottom 5 of the crate along and against the side crate walls 6. The end marginal portions of the lower plate 14 are bent upwardly to provide flanges 18 which extend along and against the side faces of the end walls 7 of the crate, such flanges 18 being preferably secured to such end walls 7 as by the nails 19 or other fastenings.

Below the plate 14 are reinforcing ribs, also preferably formed of sheet metal bent into a substantially inverted V shape in cross section and including the divergent legs 20 and 21. These legs rest at their lower wider portions upon the bottom 5 of the crate and extend upwardly into the ridge 22, which ridge extends in contact with the lower sur-

face of the lower plate 14 and supports the same. Any desired number of the reinforcing ribs may be provided.

In the drawing, I have shown for illustrative purposes, three such ribs, the ribs being placed between longitudinal rows of the bottle openings 15, so that the crest portions or ridges of the reinforcing members are in contact with the plate 14 throughout the entire length thereof. The end portions of the legs 20 and 21 are bent outwardly to provide ears 23. It is, of course, first necessary to slit the reinforcing strip along the ridge for a distance from each end and then to bend outwardly the ears 23 so that they will be in a substantially vertical plane and lie flat against the end wall 7, to which they may be affixed as by the nails or other fastenings 24.

The openings in the upper and lower plates 8 and 14 will, of course, be in alignment to receive the bottles 13.

In the use of the device, the bottles are inserted in the crate in the manner indicated by dotted lines in Figure 2, the bottle projecting through registering openings in the plates 8 and 14 and resting directly upon the bottom 5 of the crate. The flanges 12 and 16 of the plates will embrace the sides of the bottle 13 and serve to effectually hold the bottle in place and against destructive side movement.

Now it is an easy matter to insert the bottoms of the bottles through the openings 11 in the upper plate 8 on account of its proximity to the user of the device, but often the bottles are dropped down not precisely in a vertical direction, and they often strike the lower plate and would ordinarily do injury thereto, dislocating or displacing locally portions of the lower plate downwardly so that the alignment of the openings would be in a short time destroyed and the lower plate otherwise injured and broken. However, this situation is taken care of by the reinforcing strips which serve to support the plate, particularly adjacent the openings. Now it will be apparent that the two plates and the reinforcing ribs may be readily applied to any wooden box or crate. After their application, the wooden structure of the box or crate is greatly strengthened and at very small expense. Should one or the other plates or reinforcing ribs become broken or worn through use or age, the same can be very readily removed and discarded and replaced by a new similar part at very little expense, and when these parts become broken or worn it is not necessary to discard the entire crate, but the broken parts may be renewed and the crate maintained for a long period of time in a useful condition.

It will be obvious that various changes in the construction, combination and arrangement of parts could be made, which could be used without departing from the spirit of

my invention, and I do not mean to limit the invention to such details, except as particularly pointed out in the claim.

Having thus described my invention, what I claim and desire to secure by Letters Patent of the United States is:—

An improved crate comprising a crate body, composed of a bottom, sides and ends, an upper sheet metal plate, having openings therein with down-turned marginal flanges, said plate resting upon the sides and ends of the crate and having down-turned external flanges embracing the outer faces of the side and end walls and being affixed to said walls, a lower plate having openings therein with the reinforced marginal flanges lying in the lower portion of the crate body, legs at the sides of the plate bent downwardly therefrom and resting upon the bottom and in contact with the side walls of the crate, and flanges bent upwardly from the lower plate and lying in contact with the end walls of the crate and affixed thereto, longitudinal reinforcing ribs having diverging legs resting upon the bottom of the crate and having upper joining ridges contacting with the lower side of the lower plate, said ribs having split and out-turned ends placed against and affixed to the end walls of the crate.
